UNITED STATES PATENT OFFICE

EBENEZER B. HURFORD, OF NEW YORK, N. Y.

SIGN

Application filed April 21, 1931. Serial No. 531,680.

This invention relates to improvements in signs, and more particularly to a changeable type of sign.

Among the principal objects which the invention has in view are: To provide a device which may be readily changed; to provide a device with means therein to accessibly adjust the reading matter; to provide a device having a number of independent tapes with written matter thereon; to provide means whereby each tape may be operated independently; to secure simplicity of construction and operation; and to obtain other advantages and results as may be brought out in the following description.

In the drawing:

Figure 1 is a front view of my improved device and with the cover partially cut away to view the operating mechanism;

Figure 2 is a transverse sectional view shown as taken on the line 2—2 of Figure 1;

Figure 3 is a fragmentary longitudinal sectional view shown as taken on the line 3—3 of Figure 2; and

Figure 4 is an enlarged detail view of the movable gears.

In the specification:

In the specific embodiment of the invention illustrated in said drawing, the reference numeral 10 indicates the enclosure of the device in general having side walls 11, and walls 12 and a cover 13. Said device preferably may be constructed as rectangular in shape and of a sufficient depth and width to house or enclose the operating parts. The invention contemplates means to adjust or change the titles or names and utilizes the several parts which will hereinafter be described and form essential features of the present disclosure. Said device likewise has

for a purpose the establishment of changeable signs for use in advertising current plays, pictures and so forth and may be placed over the marqueses of buildings or elsewhere, as found advantageous. At present, much time is consumed in changing titles of pictures and plays, and it is in this respect that the invention has great utility in eliminating the requirement for excessive time in making changes.

In carrying out the invention, I have shown a shaft 14 extending the entire length of the enclosure 10 within the same and adjacent one longitudinal side wall thereof. For convenience of description, the device will be considered as standing upright with the greatest length vertical, and with this viewpoint, the shaft 14 likewise assumes an upright position with the lower end projecting through the lower end wall of the enclosure. An operating means may be provided for the shaft, and as an example a swivel socket 15 is shown below the enclosure attached to the shaft. The operator may insert a suitable crank (not shown) in this socket and thereby rotate the shaft when desired.

The enclosure 10 is of any desired height and contains any desired number of means for displaying changeable letters or other units from which the complete sign will be made up. As these several means are duplicates one of the other, a description of a single means will suffice for all.

The display means each comprise a pair of reels or spools 16 upon which a ribbon or tape 17 may be wound and unwound. This tape is long enough to contain all of the letters of the alphabet or other units as well as several blanks which it may be desired to use in making up an advertisement or other display. The spools 16 are frictionally engaged by springs 18 so that the tape will be held tight and remain in the position to which it may be moved. Furthermore, as here shown, idler rolls 19 are provided parallel to the spools, said idler rolls being in a plane parallel to the cover 13 and adjacent thereto so that a considerable length of the tape will be held in juxtaposition to the cover and parallel thereto. The cover has windows 20 through which the letter or other display unit may be seen. In the drawing three sides of the window is shown as boarded by a grooved frame 21 adapted to receive a pane 22 of glass or other transparent or translucent material of any desired color and transparency to accomplish the desired effect.

As here shown the spools 16 are journaled in end plates 23 mounted within the enclosure parallel to the longitudinal side walls. These

end plates likewise provide supports in which to journal the idler rolls 19 and upon which to mount the friction tension springs 18. The spools are each fast upon a spool shaft 24 or its equivalent and one end of the shaft 14 projects through the end plate 23 toward the main shaft 14. Preferably the spool shafts and the main shaft are all in a common plane with all of the spool shafts parallel and perpendicular to the main shaft. Splined upon the main shaft is a sleeve 25 at the opposite ends of which are provided bevel gears 26, 26, here shown as facing away from each other. Between the bevel gears 26, 26, are 10 preferably provided a pair of spaced collars 27, 27, by means of which the sleeve may be shifted longitudinally upon the shaft. By way of illustration, the splining of the sleeve upon the shaft is accomplished by a slot 27' longitudinally of the sleeve and receiving a pin 28 projecting radially from the shaft. At the end of each spool shaft 24 is a bevel gear 29 adapted to mesh with one of the bevel gears upon sleeve 25. The proportions are 20 such that only one gear 26 on the sleeve can be in mesh at one time.

A gear shifting lever 30 is hinged to a bracket 31 carried by the housing behind the main shaft so that the said lever may project 30 past the shaft at substantially right angles thereto and protrude at its forward end through a slot 31 in the cover 13. This lever is preferably constructed so that its outer end can be tilted through a small angle as indicated by dotted lines in Figure 2 away from the shaft. Beneath the cover 13 is provided a notched detent 32 of such a character that the lever is normally within one of the notches, but may be tilted out of the notch 35 when desired to swing the lever in a direction longitudinally of the shaft. A spring 33 suitably positioned as between the end plate 23 and lever 30 under tension may be provided to hold the lever tilted normally into one of the notches. The lever 30 provides a projection 34 at an appropriate position which lies between the collars 27, 27. When the lever 30 is swung longitudinally of the shaft, said projection 34 engages one or the other 40 of the collars and moves the sleeve longitudinally of the shaft. I preferably provide three notches for holding the lever, the extreme notches holding the lever with one or the other gear on the sleeve in mesh with the corresponding gear of the adjacent spool, and the third notch to hold the lever so that the sleeve and gears will be in neutral position. When it is desired to change any letter or character showing through one of the 45 windows, the lever is swung to mesh the gear for the proper spool and the main shaft is then rotated until the letter appears. The lever is then swung back to neutral position. 50 Another letter may then be adjusted without

disturbing the first, and so on until the sign has been changed as desired.

Each letter is preferably illuminated, and for that purpose I have shown the two spools of each pair separated and a suitable illuminating bulb 35 is provided in a position underlying the gap between the spools such that the light therefrom will pass through the portion of tape on which the desired display appears. Part of the tape may be more opaque than another part so that the letter will be visible by virtue of the light. For instance, the tape may be opaque and the letters may be translucent.

It is to be understood that while I have shown and described the sign of my invention in an upright position, and have utilized letters, tape, and other parts of specific construction, the same has been done with a view to showing one embodiment only with a full realization that these and other parts may be materially altered both in position and character and still fulfill the purposes of the invention. The variations in position and substitution of equivalents are included within the scope of my invention without attempting to illustrate more of them in the present disclosure. It will be noted in the construction herein shown that each unit is made up with its own pair of spools and its own side plates, control lever and light bulb, so that repairs and replacements may be made with respect to any one of the units without affecting any of the others.

I claim:

1. A device as characterized comprising an enclosure, a series of units within the enclosure, each unit having a tape for exposing written matter in a direction common to the direction of exposure of the written matter of the other tapes and said enclosure having a series of windows all facing in the same direction for simultaneously exposing the written matter of the several tapes, a pair of spools for each tape, said spools of the pairs being parallel to each other and all of said pairs of spools being parallel, a gear at the end of each spool, a shaft arranged longitudinally of the series of units and transverse to the several spools adjacent the several said gears, and sleeves on said shaft, one for each unit and having cooperating gears at the opposite ends of each sleeve spaced a less distance than the spacing of the respective pairs of gears of each unit and adapted to be slid to mesh either one with the gear of the spool or disengaged from both said gears, whereby the shaft may be continuously operated and affect only the unit desired to be affected.

2. A device as characterized comprising an enclosure, a series of units within the enclosure, each unit having a tape for exposing written matter in a direction common to the direction of exposure of the written matter

of the other tapes and said enclosure having a series of windows all facing in the same direction for simultaneously exposing the written matter of the several tapes, a pair of 5 spools for each tape, said spools of the pairs being parallel to each other and all of said pairs of spools being parallel, a gear at the end of each spool, a shaft arranged longitudinally of the series of units and transverse to 10 the several spools adjacent the several said gears, and sleeves on said shaft, one for each unit and having cooperating gears at the opposite ends of each sleeve spaced a less distance than the spacing of the respective pairs 15 of gears of each unit and adapted to be slid to mesh either one with the gear of the spool or disengaged from both said gears, whereby the shaft may be continuously operated and affect only the unit desired to be affected, and 20 means for individually and separately operating said sleeves.
